UNITED STATES PATENT OFFICE.

WILLIAM F. PERSONS, OF LAKWOOD, OHIO, ASSIGNOR TO THE GUIDE MOTOR LAMP MANUFACTURING COMPANY, OF CLEVELAND, OHIO, A CORPORATION OF OHIO.

AUTOMOBILE-LAMP.

1,221,212.

Specification of Letters Patent.

Patented Apr. 3, 1917.

Application filed October 18, 1916. Serial No. 126,264.

To all whom it may concern:

Be it known that I, WILLIAM F. PERSONS, a citizen of the United States, residing at Lakewood, in the county of Cuyahoga and 5 State of Ohio, have invented a certain new and useful Improvement in Automobile-Lamps, of which the following is a full, clear, and exact description, reference being had to the accompanying drawings.

10 This invention relates generally to lamps and more particularly to an automobile headlight lamp.

The object of the invention is to improve the construction of automobile headlights 15 particularly with reference to the manner of securing the glass and reflector to the body of the lamp.

With this object in view the invention consists essentially in constructing the body 20 of the lamp with a flat outer edge against which rests the flanged portion of the reflector, this reflector in turn receiving the glass or glazing thereagainst, the glass and reflector being securely held in their proper 25 positions by means of a continuous glass holding ring curved along its inner edge to engage the glass and flanged along its outer edge to embrace the body portion of the lamp, the glass holding ring being secured 30 by means of a divided clamping ring adapted to embrace the glass holding ring and the outer portion of the lamp body.

The invention consists also in certain details of construction all of which will be 35 fully described hereinafter and pointed out in the appended claims.

In the drawings forming a part of this specification I have illustrated one embodiment of my invention, but it will be understood 40 that certain changes or modifications can be made within the scope of the claims.

In these drawings Figure 1 is a face view of an automobile lamp embodying my invention, parts being broken away to illustrate certain details of construction; Fig. 2 is a vertical longitudinal section of the lamp; Fig. 3 is a detail perspective view of the clamping ring; Fig. 4 is a sectional perspective of the glass holding ring; Fig. 5 is a detail sectional view illustrating the means for fastening the ends of the clamping ring; and Fig. 6 is an enlarged detail sectional view illustrating the relative positions of the various parts when properly 45 assembled.

In carrying out my invention I employ an outer shell or body 10 which may be of any shape desired, the forward outer edge thereof being rolled downwardly at 11 and inwardly at 12, the portion 12 being flat 60 and at right angles to the portion 11 as most clearly shown in Fig. 6. A slight shoulder 13 is provided where the body portion and the roll meet.

The reflector 14 is constructed with an 65 outwardly extending flange 15 which rests upon the inturned portion 12 of the lamp body, and this flange of the reflector is preferably formed with an annular groove or recess 16 in which seats the packing ring 70 17, of any suitable material; and resting upon this packing ring is the circular glass plate or glazing 18.

In practice, I prefer to so position the annular groove in the reflector flange that a 75 snug fit will be made between the reflector and the inturned edge of the lamp body as most clearly shown in Fig. 6, but this detail is not necessary and any other construction may be employed, provided the 80 flange of the reflector has a firm seat against the lamp body at the outer edge thereof.

In order to hold the glass firmly against the reflector with its packing ring, I employ a continuous glass holding ring 19, 85 the inner portion thereof being curved as shown at 20 so as to contact with the glass adjacent its outer edge, and the outer portion of this ring is flanged as shown at 21 in order to embrace the outer edge of the 90 lamp body, and between the flanged portion 21 and the curved portion 20 there is formed an inwardly extending shoulder 22 which is adapted to contact with the inturned edge 12 and properly position the glass holding 95 ring.

For the purpose of securely fastening the glass holding ring against displacement I provide a clamping ring 23 divided at 24 and having upset ends 25 and 26, the end 100 26 being shaped to receive the end 25 therein and provide a perfectly smooth joint. For the purpose of drawing the ends of the clamping ring together and binding the entire ring as a whole tightly about the lamp 105 body and glass holding ring, I employ a screw 27 working in the threaded member 28 carried in the end 25, and if desired a similar shaped member 29 may be inserted in the offset end 26 for the purpose of 110

strengthening the same and through which the screw works as most clearly shown in Fig. 5.

The clamping ring 23 is curved or of such cross sectional shape as to embrace the shouldered portion of the glass holding ring and also the shoulder 13 upon the lamp body, and it is obvious that when the ends of the ring are drawn together and the ring as a whole contracted it will be firmly bound upon the lamp body and all of the parts will be securely fastened in their proper positions.

A lamp constructed as herein shown and described is easy to manufacture, and the parts can be quickly and easily assembled and fastened or unfastened and separated; and all of the parts so coact and cooperate one with the other, as to insure accuracy of adjustment in the final manipulation.

Having thus described my invention, what I claim is:

1. In a lamp, the combination with a body portion, of a reflector arranged therein, a glass in advance of said reflector, a glass holding ring contacting with said glass, and an exterior clamping ring engaging and embracing an edge of the glass holding ring and body of the lamp.
2. In a lamp, the combination with a body portion, of a reflector positioned therein, a glass in advance of said reflector, a sheet metal glass holding ring contacting with said glass adjacent the outer edges thereof, and a divided exterior clamping ring adapted to engage the glass holding ring and lamp body.
3. In a lamp, the combination with a body portion, of a reflector positioned therein, a glass contacting with said reflector, a continuous flanged glass holding ring contacting with said glass, a divided exterior clamping ring adapted to engage said glass holding ring and the body of the lamp, and means for contracting said clamping ring upon said glass holding ring.

4. In a lamp, the combination with a body portion, of a reflector positioned therein, a glass in advance of said reflector, a flanged sheet metal glass holding ring contacting with said glass adjacent its outer edges, a divided exterior clamping ring adapted to engage the glass holding ring and lamp body, the ends of said divided ring being upset, and a screw working in said upset ends for drawing the same together.

5. In a lamp, the combination with a body portion, of a reflector and glass positioned therein, a continuous glass holding ring adapted to embrace the outer edges of the lamp body and contact with the glass, and an exterior clamping ring adapted to engage the glass holding ring and lamp body.

6. In a lamp, the combination with a lamp body having a reflector and glass positioned therein, of a continuous flanged glass holding ring adapted to contact with the glass and embrace the outer edges of the lamp body, and an exterior clamping ring adapted to engage the glass holding ring and the lamp body.

7. In a lamp, the combination of a body portion, of a flanged reflector positioned therein, a glass positioned upon said reflector, a continuous, flanged, glass holding ring contacting with said glass and embracing the outer edges of the lamp body, a divided exterior clamping ring adapted to engage the glass holding ring and lamp body, and means for drawing the ends of said divided ring together.

8. In a lamp, the combination with a body portion having an inwardly rolled front edge, of a flanged reflector, a glass, and a glass holding ring, said ring being flanged, shouldered and curved, a divided clamping ring curved in cross section, and means for contracting said clamping ring.

In testimony whereof, I hereunto affix my signature.

WILLIAM F. PERSONS.
